UNITED STATES PATENT OFFICE.

FREDERICK P. AMES, OF KANSAS CITY, MISSOURI, ASSIGNOR TO ASKEW SADDLERY COMPANY, OF KANSAS CITY, MISSOURI, A CORPORATION OF MISSOURI.

GIG-SADDLE.

1,111,686.

Specification of Letters Patent.

Patented Sept. 22, 1914.

Application filed June 18, 1912. Serial No. 704,333.

To all whom it may concern:

Be it known that I, FREDERICK P. AMES, a citizen of the United States, residing at Kansas City, in the county of Jackson and State of Missouri, have invented certain new and useful Improvements in Gig-Saddles; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to a seat for gig saddles or coach pads, and has for its principal object to provide a seat of this character which may be securely fastened to the saddle or pad, so that it will not become loosened after continued use. In accomplishing this object I have provided the improved details of structure hereinafter described and illustrated in the accompanying drawings, wherein:—

20 Figure I is a perspective view of a saddle equipped with a seat constructed according to my invention. Fig. II is a longitudinal section of the seat and the central portion of the saddle. Fig. III is a detail view of the seat.

25 Referring more in detail to the parts:— 1 designates the saddle housing, 2 the pad, and 3 a jockey, which may be of ordinary construction.

30 In the drawings I show the saddle body as comprising spaced metal straps 4—4', which are connected at the center by a loop 5, and elsewhere throughout the saddle by any suitable means, the latter, however, not 40 being illustrated in detail, as the saddle *per se* forms no part of my present invention.

45 Mounted on the arch of the saddle and directly overlying the jockey is a seat 6, which is of the ordinary construction, except that it is provided with lateral ears 7, which hang over the sides of and are curved to conform to the curve of the pad, the ends of the ears being provided with apertures 8, through which the fastening bolts 9 are projected. The bolts 9, after passing through the strap ears, extend through the pads,

through the saddle housing and body and through nuts 10, which latter are located between the saddle straps 4—4', the heads of the bolts being preferably rounded, as shown, 55 in order to obviate sharp edges at the top of the saddle, and being provided with sockets 11 for receiving the points of a wrench, whereby the bolts are tightened. In the center of the seat is an aperture 12 for receiving 60 the hook shank 13, which latter carries a nut 14 on the underside of the pad to fasten the hook in place and assist in connecting the other parts of the saddle. A seat of this description is fastened to the saddle by the 65 hook, in the ordinary manner, and also by the end bolts 9, thereby insuring a much firmer attachment of the seat, so that the usual loosening of the seat from the saddle is obviated.

70 Having thus described my invention, what I claim as new therein, and desire to secure by Letters Patent is:—

1. The combination with a reinforced, arched saddle, of a seat comprising a body, 75 a crupper loop integral with the body, laterally extending reinforcing ears integral with the body and secured near the outer ends to the reinforced saddle, and a rein hook having a square shank projected 80 through and adapted to secure the central portion of said body and saddle.

2. The combination with an arched saddle having a metal reinforcing member, of a stamped metal seat comprising a body portion having a square aperture therein, a crupper loop integral with the body, laterally extending reinforcing ears integral 85 with the body and secured to the saddle and reinforcing member, a rein hook having a 90 square shank projected through the square aperture in the body and through the saddle, a threaded extension on said square shank, and a nut on said extension for drawing the central portion of said seat, saddle and reinforcing member firmly together.

95 In testimony whereof I affix my signature in presence of two witnesses.

FREDERICK P. AMES.
